SET OF ORNAMENTAL INITIALS FOR SPECTACLE FRONTS

Samu-El Ish-Shalom, New York, N. Y.

Application April 10, 1952, Serial No. 19,271

Term of patent 14 years

(Cl. D57—1)

To all whom it may concern:

Be it known that I, Samu-El Ish-Shalom, a citizen of the United States of America, residing at New York, N. Y., have invented a new, original, and ornamental Design for a Set of Ornamental Initials for Spectacle Fronts, of which the following is a specification, reference being had to the accompanying drawings, forming a part hereof.

Fig. 1 is a front elevational view comprising initials A to M of ornamental initials for spectacle fronts showing my new design;

Fig. 2 is a similar view comprising the initials N to Z; and

Fig. 3 is a typical side elevational view showing the letter B.

I claim:

The ornamental design for a set of ornamental initials for spectacle fronts, as shown.

SAMU-EL ISH-SHALOM.
